UNITED STATES PATENT OFFICE.

THOMAS C. ENTWISTLE, OF LOWELL, MASSACHUSETTS.

EXPANSION COMB OR REED FOR WARPING OR BEAMING MACHINES, &c.

SPECIFICATION forming part of Letters Patent No. 252,089, dated January 10, 1882.

Application filed September 27, 1881. (No model.)

To all whom it may concern:

Be it known that I, THOMAS C. ENTWISTLE, of Lowell, Massachusetts, have invented certain new and useful Improvements in Expansion Combs or Reeds for Warping or Beaming Machines and other Purposes, of which the following is a specification.

The ordinary expansion-comb used on warping or beaming machines, and on slashers for the purpose of guiding the threads to their proper places upon the beam on which they are wound, consists of a series of teeth or dents mounted at their lower ends on a wire or rod, on which they can slide to and from one another, in combination with a number of spirally-coiled wire springs arranged lengthwise of the comb, between the coils or turns of which springs the dents extend. When the springs are expanded, by means of suitable screws or other stretching devices which draw upon the ends of the springs, their coils separate, and consequently the dents are drawn apart, so as to leave wider spaces between them. When, on the other hand, the springs contract, the dents are brought closer together, and in this way any desired number of dents can be brought into use. The main objection to the use of this form of expansion-comb is that the springs are apt to become weak at the ends where the tension is applied to them, so that their coils or folds open and the springs lose, in a measure, their resiliency at those points, thus becoming unfit for use. Even under the best conditions the springs will expand more toward their ends than at the center, thus laying the selvage-threads upon the beam more loosely and more widely separated than the threads which are nearer the center.

It is my object to remedy these and other objections, and to obtain an expansion-comb in which the expansion and contraction shall be the same for every part of the comb.

To this end I form the comb of a series of dent-carrying sections jointed or hinged together in such manner as to permit them to move on their hinges in a plane transverse to the plane in which the dents stand. The sections can thus be either straightened out, so as to constitute a straight bar, or they may be set in zigzag fashion, so as to contract the working length of the bar. The dents set in the sections are widest apart when the sectional bar is straightened out. When the sections,

however, are brought into zigzag order the dents no longer stand in a straight line at right angles to the thread; but the line of dents of each section stands obliquely to the threads, so as to present less space between each two dents for the passage of a thread. The less obtuse the angle at which the sections stand to one another the more the comb is contracted and the greater the number of teeth brought within a given space. To arrange this sectional jointed comb so that the expansion and contraction shall be the same throughout its length, I place it in a box, one side of which is movable to and from the other. With the sections I combine springs, which tend to draw the sections out of line with one another. When the movable side of the box, by suitable devices, is drawn toward the other side the sections are straightened out more or less, and the comb is correspondingly expanded. When, on the other hand, the movable side is allowed to recede from the other side, the springs act to bend the sectional bar at the joints, and the comb is correspondingly contracted. Inasmuch as the comb is acted on at each joint there must be necessarily the same expansion and contraction throughout all parts of the comb.

In the accompanying drawings is represented an expansion-comb embodying my invention in one practicable form.

Figure 1 is a plan of the comb and comb-box. Fig. 2 is an elevation of the same, with the movable rail broken away. Fig. 3 is a plan of the under side of the comb-box. Figs. 4 and 5 are a plan and an elevation, on enlarged scale, of a portion of the comb and comb-box.

The comb or reed is composed of a suitable number of bar-sections, A, jointed together at a, and each armed with dents or teeth B, of wire, set firmly in the tops of the sections.

The box for holding the comb consists of a bottom plate, C, provided on one of its longer edges with a fixed upright flange or rail, D, which forms one of the sides of the box. The other side is formed by a parallel rail or bar, E, movable in parallel planes to and from the stationary side. It is for this purpose held to the base-plate C by headed studs or guide-pins b, which pass down through slots c in the base-plate. The movement of the rail or bar E to and from the other rail may be accom-

plished by a variety of means. The mechanism for this purpose (shown in the drawings) consists of vibratory angle-levers *d*, pivoted at *d'* to the under face of the base-plate, and en-
 5 gaging pins *e*, which project from lugs *e'*, formed on the bottom of the rail *E*, and enter slots *e²* in the adjoining arms of the angle or bell-
 10 crank levers. The other arms of the said levers, at their outer ends, are pivoted to a com-
 mon rod, *f*, to which, at one end, is swiveled
 15 an adjusting-screw, *g*, which is held in a bearing-nut, *h*, swiveled to the base-plate. The lugs *e'* move in slots *d²* cut in the base-plate, of a length sufficient to permit the requisite
 20 traversing movement of the lugs. By means of the adjusting-screw the bell-crank levers are vibrated in one direction or the other, and according to the direction and extent of the
 25 vibratory movement of the levers the movable side *D* of the box is caused to approach or recede from the other side, *E*, to the degree desired. The comb is set upright on base-
 30 plate between the two rails or sides *D E* of the box; and in order that it may expand and contract equally to each side of the center, it should be fastened at that point to the box, for which purpose the pintle or hinge-pin which
 35 unites its middle sections (indicated at *w*) may be set or fixed in the base-plate *C*. When the side or rail *E* is moved toward the other side, *D*, the box is narrowed and the comb conse-
 40 quently is expanded, its sections being forced to stand at a more obtuse angle to one another. When the side *E* is moved in the op-
 45 posite direction the box widens, and conse-
 50 quently the sections can stand at a less obtuse angle to one another, thus contracting the comb and bringing more dents into the working field.
 40 The rail *E* forces the expansion of the comb by bringing pressure against it at the joints; but it only permits the contraction. It is required therefore to employ some means of compelling the comb-sections to follow the movement of the receding rail. To this end I make use of spiral springs *i*, each fastened at one end to one section and at the other end to the next adjoining section, so as to span the angle between the two sections. These springs are put
 55 under tension when the comb expands, and consequently cause its contraction to the extent permitted by the rail *E*. This spring arrangement is convenient, simple, and effective. Other arrangements, however, manifestly may be made use of for the same purpose, and with

the same effect. I do not therefore restrict myself to the arrangement shown in the drawings.

It will be seen that the less obtuse the angle at which the sections stand to one another the greater the number of dents or teeth brought within a given length of comb, so that by varying the angle at which the sections are placed with respect to each other any desired number of dents may be brought into the working field. It will also be observed that the expansion and contraction are the same for every part of the comb.

Having described my invention and the best way, on the whole, known to me of carrying the same into effect, I observe, in conclusion, that the mechanical details of construction may be considerably varied without departure from my invention. I do not therefore confine myself to the particular instrumentalities herein shown; but

What I claim as of my own invention is as follows:

1. An expansion comb or reed for warping-machines and other purposes, consisting of a series of dent-carrying sections hinged together, substantially as and for the purposes hereinbefore set forth.

2. The comb sections hinged together and provided with dents or teeth, in combination with springs connected to adjoining sections, substantially as and for the purposes hereinbefore set forth.

3. An expansion-comb composed of sections hinged together and armed with dents or teeth, in combination with a comb box or holder; and means, substantially as described, for setting the comb-sections at varying angles with respect to one another, substantially as and for the purposes hereinbefore set forth.

4. The comb-sections provided with dents and hinged together, in combination with a comb-box having one side or rail movable to and from the other, so as to narrow and widen the box, means for adjusting the same, and springs which move the comb-sections in a direction opposite to that in which they are moved by the movable box side or rail.

In testimony whereof I have hereunto set my hand this 23d day of September, 1881.

THOMAS C. ENTWISTLE.
